UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,271,289.

Specification of Letters Patent.

Patented July 2, 1918.

Application filed March 17, 1913. Serial No. 754,709.

To all whom it may concern:

- Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.
- 10 This invention relates to combined typewriting and computing machines, particularly those which are adapted to do computing in a number of different columns.
- As herein illustrated, this invention is applied to a combined typewriting and computing machine of the Underwood-Wright type, in which the carriage of the typewriter carries a platen on which the writing sheet is placed. This platen, as in an ordinary typewriter, has a letter-feeding motion and is arranged in said motion to control the *scriptum* connection between the numeral keys of the typewriter and the computing wheels of the computing mechanism proper.
- 25 For this purpose in said combined machine the computing wheels are mounted in a totalizer, and the master-wheel is connected to said carriage to be moved thereby so as to engage the computing wheels in said totalizer *scriptum*. For computing in several columns or zones tabulator stops may be provided which are arranged to automatically establish and let go said connection between the typewriter carriage and the master wheel in the totalizer. This enables writing done on a work-sheet in several different columns to be computed in one totalizer as though it were in a single column. This connection between the tabulator stops and the master wheel may be made by a hook adjacent the typewriter carriage, and every time the typewriter carriage carries a stop past said hook, it automatically catches the hook by means of the stop and thereby causes said master wheel to be moved by the hook, for predetermined distances. A cam on the hook may be arranged to ride under a stud and force said hook free of said stop when beyond every computing zone.
- 40 The present invention is illustrated as applied to a computing machine having a plurality of totalizers separately connectible to the numeral keys. For the purpose of vary-
- ing the nature of the connections between the numeral keys and the computing wheels, 55 the stops may be provided with projections, which, in the travel of the typewriter carriage, are arranged to shift a clutch or clutches in the gearing between said wheels and said keys. Each of these clutches, for 60 example, in one position may cause the master wheel to rotate the computing wheels so that they add, in another position may rotate them so that they subtract, or the clutch may be absolutely neutral, as the case 65 may require. The stops may control each clutch separately by means of cam arms hung in the typewriter frame, which arms are drawn by springs to engage said stops as the stops travel with the typewriter carriage. 70
- Each totalizer has an individual converting mechanism, and there is no liability of one converting mechanism controlling the totalizer which belongs to the other converting mechanism, since neither master wheel 75 can possibly reach the totalizer belonging to the other master wheel, as the totalizers are shown as having preferably a tandem or axially offset arrangement, preferably one above the other, and the master wheels have 80 a corresponding arrangement.
- Other features and advantages will hereinafter appear.
- In the accompanying drawings,
- Figure 1 is a diagrammatic side view of 85 an Underwood-Wright typewriting and computing machine, showing my invention applied thereto.
- Fig. 2 is a perspective view of some principal parts of the computing mechanism. 90
- Fig. 3 is a section through a totalizer.
- Figs. 4 and 5 are respectively plan and perspective views of the connection between the tabulator stops and the totalizer.
- Fig. 6 is a detail of the same. 95
- Fig. 7 is a perspective view showing some parts especially connected with the present invention.
- Fig. 8 is a rear view of the same.
- Fig. 9 shows various combinations of automatic stop-controls. 100
- Numeral keys 1 and letter keys 2 of the typewriter depress levers 3 to cause bell cranks 4 to swing type bars 5 upwardly and rearwardly against the platen 6, so that 105 type 7 will write on a work-sheet thereon.

Said platen is mounted in a carriage 8, traveling on rails 9 and 10, and said carriage is drawn forward in letter-feeding direction by means of a spring barrel 11, 5 and is controlled in said letter-feed by means of an escapement wheel 12, carrying a ratchet wheel 13 which works in a rack 14 mounted on the carriage. Said escapement wheel is controlled by means of dogs 10 15 and 16, which dogs are operated by an extension 17 of a universal member 18, which universal member is operated by heels 19 on the type bars as they rise toward the platen.

15 Each numeral key as it is depressed is arranged to operate the valuating or indexing mechanism escapement, so as to cause the numbers written to be carried into the computing wheels. For this purpose each 20 numeral key is engaged by a link 20 depending from a bell crank 21, which bell crank is joined by a link 22 to the computing mechanism proper. When the key 1 is depressed, it draws link 22, so as to cause the 25 lever 23 to thrust forward a digit-determining jack 24 and sets a pin 25 of a valuating or index wheel 26. At the same time a universal disk 27 is drawn backward by the head of said link 22, so that the lever 28 30 rocks the link 29 controlling a secondary escapement, and said secondary escapement comprises a star wheel 30, which has been holding the escapement wheel 26 against revolving by means of a pin 25 thereon, 35 which had been previously projected.

The wheel 26 constantly tends to be turned by a motor 31 through a friction 40 clutch, not shown, bevel gears 32, 33, and a shaft 34, which shaft has fast to it a bevel gear 35, meshing with a bevel gear 36; and said bevel gear 36 is fast on a shaft carrying a gear wheel 37, which in turn meshes with a gear wheel 38 fast to the index or valuating wheel 26. As the link 29 45 is moved forward at the depression of the key, it allows an escapement tooth 39 fast on the shaft of star-wheel 30 to escape past a dog 40, so that it strikes a dog 41, and on the return stroke of said numeral key, 50 said tooth 39 escapes from the dog 41 and allows the wheel 26 to carry around its pin 25 which has been bearing against the star-wheel 30, so that said wheel 26 can turn until the tooth 25, which has just been projected by the jack 24, strikes the succeeding tooth of the star wheel 30. Said wheel 26 55 is then held against revolution by means of a second tooth 39, which has been brought around to bear against the dog 40 when the pin 25 strikes the tooth of the star wheel 30.

As the motor 31 turns said wheel 26, it turns the bevel gear 42, which is constantly in mesh with the bevel gear 36, and will, through shaft 43, turn the vertical shaft 44 60 by means of bevel gears 45 and 46, and in

so doing will cause the number then written to be carried into a totalizer 47. The projected pin 25, which has been previously engaging the star wheel 30, is returned by a cam wiper, not shown herein, after it 70 passes said wheel.

In the machine herein shown, there are two totalizers 47, which may be identical and the description of one will answer for both. In each of said totalizers 47 there is 75 a series of computing wheels 48, which are arranged to be engaged *seriatim* by means of a master wheel 49 lying within said computing wheels and arranged to be carried back and forth within said wheels to engage them *seriatim* in a manner presently to be described.

When engaged with any computing wheel 48, said master wheel is arranged to be turned by means of a square shaft 50 on 80 which it is slidably mounted, and said shaft extends through the frame of the machine at 51 where there is fast on it a bevel gear 52, which is arranged to mesh with bevel gears 53 and 54 on shaft 44, and to be turned 85 by one of them in a manner to be herein-after described. Said master wheel, as will be seen, comprises a hub 55, which is freely revoluble in a sleeve 56, which sleeve, however, moves said master wheel successively 90 into engagement with the various computing wheels. For so moving it, there is provided on the carriage 8 of the typewriter a rack bar 57 carrying settable lugs 58, which lugs are arranged to successively engage, as seen in Fig. 5, a hook 59 comprising a notch 60 in which said lugs rest when moving it.

Said hook 59 is formed as the end of a sliding rod 61 in the casing 62 fast on the 105 typewriting machine. Projecting downwardly from said rod through a slot 63 in the casing, is a pin 64 engaging one arm of a lever 65, which is pivoted at 66, of which lever the two opposite arms 67 and 68 engage carriages 69, of which carriages the sleeves 56 controlling the *seriatim* engagement of the master wheels form a part. This lever 65, as seen from the rear and above in Fig. 4, is normally drawn to the 110 right by means of a spring 70 anchored in the frame of the machine, and in such position causes the master wheels 49 to engage the highest wheel in each of said totalizers. From such position it is drawn by means of 115 the hook 59, as above described, so that at each letter-space movement of the typewriter it moves the master wheels to engage step by step with the various computing 120 wheels.

When said hook 59 has drawn the master wheels so that they engage with the units computing wheels, the cam end 71 of the hook is caused to release said hook from the stop 58 by striking a pin 72 fast on the 125 130

frame of the machine, under which pin said hook is drawn until it swings downward clear of the stop 58, and then is drawn backward to the highest computing wheel by the 5 spring 70. Said hook 59 is held upward in position where the next stop 58 will strike it by means of a spring 73 bearing against a screw 74 entered in a socket in the frame of the typewriting machine.

10 The lever 65 is slotted at each end where it engages the pins 64 and 75, the latter pin being the means by which it is connected to the carriage 69, which causes the step-by-step movement of the master wheel. Said 15 carriage 69 comprises, in addition to the sleeve 56, a sleeve 76, which embraces a rod 77 fast on the frame of the typewriting machine and carrying in its opposite end a cross rod 78, which cross rod also supports 20 the outer end of a rod 79, said rod 79 embraced by the plate 80 forming the union between the sleeves 56 and 76 of the master wheel carriage.

When returning the carriage 8 to begin a 25 new line of writing, if the hook 59 is in engagement with one of the stops 58, it is carried to the left in Fig. 5 until the cam edge 81 thereon strikes a stud or roller 82, which may be pivoted on a screw 83 threaded into 30 the top of the boss 84 on which the screw 83 is mounted, and by means of said roller, the hook is cammed downwardly and released from the stop 58. The spring 73 immediately raises the hook, and the stops 58 in 35 succession ride freely over a bevel or point 85 on the tip of the hook, the last stop in the series being caught and held by the hook when the carriage begins to run in letter-feeding direction.

40 The totalizer 47 comprises a casing 86, through a sight opening 87 in which numerals of the dial wheels 88 may be read. Each dial wheel is constantly in mesh with its computing wheel 48, and said computing 45 wheel carries internal teeth 90, as seen in Fig. 3, arranged to be engaged by the teeth 91 of the master wheel 49. Each computing wheel also is constantly in mesh with a carry-over wheel 92 comprising three different forms of teeth. Of these forms of teeth, one set 93 constantly meshes with the teeth of the computing wheel 48, so as to turn said wheel when the carry-over wheel is turned one units space by the computing wheel next 50 lower in denomination. Each computing wheel also comprises a special tooth, not shown herein, which is arranged to strike a tooth 94 on the carry-over wheel geared to the computing wheel next higher in denomination, and give that carry-over wheel a slight turn when the zero of the dial wheel turns to the sight opening 87. In giving 55 said wheel this slight turn, it moves it so that teeth 95 of the third form on said computing wheel engage resilient roll 96 which

is power-driven, and said roll completes the turning of the carry-over wheel its one unit space. Said resilient roll 96 is driven by a gear wheel 97 meshing with a gear fast on it, which gear wheel in turn is driven by a 70 pinion 98 fast on its shaft, and said pinion is driven by a gear wheel 99 fast on a shaft 100, which is geared to the motor through a bevel gear 101, as will be presently described.

It has been stated that the wheels in the 75 totalizer may be turned either to add or subtract, and for this purpose on the shaft 44 which drives said wheels, as described above, there is formed a clutch 102 for each totalizer, comprising a member 103 slidably 80 splined on said shaft 44 and arranged to lock internally with either the upper bevel gears 54 or the lower bevel gears 53, which bevel gears turn loose on said shaft. The member 103, for this purpose, may be shifted 85 by means of a handle 104 pivoted at 105, and on the rearward extension of said handle is formed a series of notches 106 arranged to engage a detent 107 and hold said clutch member in whatever position it may 90 be placed. When in its upper position, as seen at the top of Fig. 1, it will drive said wheels to add, as shown in the present instance. When said detent holds said handle 95 in its intermediate position, the clutch will likewise occupy an intermediate position, and the shaft 44 will turn without affecting the corresponding computing head or totalizer. With a handle or lever 104 in its lowermost position, the associated 100 clutch 103 will be shifted to drive the corresponding master wheel in a reverse direction, so that a subtracting operation will be performed. That is to say, with the lever or handle 104 in this latter position, a digit 105 run up into the associated computing head will be subtracted from any number accumulated therein.

For enabling the power-driven resilient 110 roll 96 of the carry-over mechanism to be reversed simultaneously with the reversal of the master wheels, a set of clutches is provided for the carry-over mechanism similar to those provided for the master wheel shafts comprising shiftable members 108, 115 which are operated by extensions of the handles 104, extending beyond the pivots 105, so as to shift said members 108 simultaneously with the shifting of the members 103 for the master wheels. Said members 120 108 are slidably splined on a shaft 109, which is driven from the motor 31 by means of a bevel gear 110 fast on said shaft 109, a bevel gear 111 meshing therewith, which bevel gear is fast on a shaft 112 carrying a bevel gear 113 meshing with a bevel gear 114 fast 125 on shaft 34.

The lugs 58, which have been above described as connecting the master wheel to the typewriter carriage so that they have 130

a similar step-by-step movement, are preferably formed as extensions of tabulating stops 115 also mounted on a rack bar 57. Said tabulating stops are arranged to coöperate with key-operated plunger stops 116 of the usual Underwood type, operated from keys 117 at the front of the keyboard, mounted on levers 118, pivoted at 119, which levers carry said plunger stops at their rear ends 10 120. Each of said tabulator keys is arranged, when it is operated, to release said typewriter carriage 8 from the escapement mechanism in the usual manner. The connections for accomplishing said release include a universal bar 121 operated by heels 122 on the stop plungers 116, and said universal bar is fast on a rock shaft 123 carrying a rock arm 124, which through a link 125 draws down the rear end of a lever 126, so as 20 to swing the front end thereof upward and cause an idle wheel 127 thereon to lift the rack 14 out of the ratchet wheel 13. When the carriage is thus released from its escapement wheel 12, it is drawn forward in letter-feeding direction until the stop plunger 116 arrests it by intercepting a carriage stop 115. Said plunger stops 116 form a decimal tabulator inclosed in a casing 128.

The carriage stops 115, in addition to the lugs or extensions 58, also include projections 129, 130 and 131. Said projections are of varying depth and are arranged to automatically shift the clutches 102, which control the turning of the computing wheels by means of the numeral keys, thus relieving the operator of the necessity of manually shifting the handles 104. For this purpose there is journaled on the casing 128 a shaft 132 carrying a rock arm 133, which rock arm 40 is arranged to coöperate with the upper end of one of the stops 115. When said rock arm 133 is held inward, as seen in Fig. 1, it rocks an arm 134 fast on said shaft 132, so as to move a forwardly extending link 135 pivoted 45 on said rock arm to swing a bell crank 136 rearwardly, so that the arm 137 thereof, which is pivoted in a slot 138 on an extension of the handle 104, will shift said handle into its downward position at the forward 50 end and cause said clutch to connect the master wheel to subtract. In the same way the lower end of the stop 115 is arranged to swing arm 139 fast on a sleeve 140 on said shaft 132, and thereby swing arm 141 fast on 55 said sleeve to draw an upper link 142, so as to cause its bell crank 143 to swing its extension 144 to swing the upper handle 104 upwardly, and thus cause said handle to add.

It will be observed that the rock arms 134 and 141 extend in opposite directions, and to offset this, the bell cranks 136 and 143 are set to work in opposite directions, so that identical lugs of the stops 115 will have identical effect on both rock arm 133 and 60 rock arm 139. Each of said rock arms 133

and 139 is drawn by a spring 145 in a forward direction constantly tending to move it to cause the computing mechanism to subtract.

In order to enable the typewriter carriage 70 to feed past the flat faces 146 and 147 of rock arms 133 and 139 respectively, the ends thereof are beveled as at 148 to form cam surfaces which will force said arms outwardly when the stops strike them. Each of the rock arms 133 and 139 is formed where it is fast onto its shaft or sleeve respectively comparatively narrow, so that the two portions thereof where fast to their shaft and sleeve will not take up more than the column 80 over which they are arranged to effect the computing mechanism. The rock arm 139 is formed with a narrow portion 149 and then at the top is extended broadly so that the edge 147 is of substantial length. The 85 rock arm 133 is formed with a narrow portion 150, which then extends to the right and then upwardly at 151, and then to the left at 152, so that the edge 146 will be of precisely the same length as edge 147, and 90 precisely above it. In this way the two rock arms 133 and 139 swing preferably clear of each other, and operate on the same column. The rock arm 133 in its narrow portion is bent outwardly at 153, so that the narrower 95 portions 149 and 150 near their tops will lie in the same plane when not engaging in stops 115.

The stops 115 may include any desired combination of adding, subtracting and neutral positions, such as are shown in Fig. 9. The rock arms 133 and 139 are locked to their carrying members by means of set screws 157 and 158, so that they may be adjusted thereon.

Variations may be resorted to within the scope of the invention, and portions of the improvements may be used without others.

Having thus described my invention, I claim:

1. In a combined typewriting and computing machine, the combination with numeral keys and a plurality of gangs of computing wheels, of a typewriter carriage, a tabulating mechanism comprising stops 115 for positioning said carriage, a bar on which said stops are mounted, a separate bar adjacent said first-mentioned bar for each gang of computing wheels, a lug on a stop for selectively operating said separate bars, 120 and a connection from each of said separate bars to the means connecting said keys and said wheels.

2. In a combined typewriting and computing machine, the combination with numeral keys and a plurality of gangs of computing wheels, of a typewriter carriage, a tabulating mechanism comprising stops for positioning said carriage, tappets on said stops, cam bars adjacent the line of travel 130

- of said stops and arranged to be moved thereby, a connection from each cam bar to its gang of computing wheels, and clutches intermediate said wheels and keys arranged to be controlled by said cam bars.
3. In a combined typewriting and computing machine, the combination with numeral keys and a traveling carriage, of a plurality of gangs of computing wheels, 10 stops on said traveling carriage, a master wheel for each gang of computing wheels, gearing connecting said numeral keys to said master wheels, clutches in said gearing, arms for controlling said clutches, and 15 lugs on said stops and means controlled by said lugs for controlling said arms.
4. In a combined typewriting and computing machine, the combination with numeral keys and a traveling carriage, of a 20 plurality of gangs of computing wheels, stops on said traveling carriage, a master wheel for each gang of computing wheels, a single shaft for driving said master wheels, a clutch between said shaft and each 25 master wheel, a bar for each clutch adjacent the carriage of the typewriter, and means for moving said bars by said stops to shift said clutches.
5. In a combined typewriting and computing machine, the combination with numeral keys and a traveling carriage, of a 30 plurality of gangs of computing wheels, stops on said traveling carriage, a master wheel for each gang of computing wheels, 35 clutches between said master wheels and keys, oppositely operable bell cranks moved by said stops and means controlled by said bell cranks for controlling said clutches.
6. In a combined typewriting and computing machine, the combination with numeral keys and a traveling carriage, of a 40 plurality of gangs of computing wheels, stops on said traveling carriage, a master wheel for each gang of computing wheels, 45 clutches between said master wheels and keys, and means for shifting said clutches by said stops.
7. In a combined typewriting and computing machine, the combination with numeral keys and a traveling carriage, of a 50 plurality of gangs of computing wheels, stops on said traveling carriage, a master wheel for each gang of computing wheels, and means controlled by said stops for 55 causing one gang to do cross-adding and another to add in one column and subtract in another.
8. In a combined typewriting and computing machine, the combination with numeral keys and a traveling carriage, of a 60 plurality of gangs of computing wheels, stops on said traveling carriage, a master wheel for each gang of computing wheels, 65 means for giving said master wheels a simultaneous step-by-step motion, means controlled by said stops for variably connecting said master wheels to said keys, and tabulating keys for positioning said carriage by said stops.
9. In a combined typewriting and computing machine, the combination with numeral keys and a traveling carriage, of a 70 plurality of gangs of computing wheels, a master-wheel for each gang of computing wheels, a series of stops, key-operated denominational stops for positioning said carriage, a universal bar operated by said key stops, extensions on the first series of stops, a rock arm carrying a cam bar arranged to be moved by an extension, a rock shaft carrying said arm, a second rock arm carrying a second cam, a rock sleeve on said rock shaft, rock arms fast on said sleeve and shaft, a clutch for each gang of computing 75 wheels, and a link from each of said clutches to one last named rock arm to shift said clutch.
10. In a combined typewriting and computing machine, the combination with numeral keys and a traveling carriage, of a 80 plurality of gangs of computing wheels, stops on said traveling carriage, a master wheel for each gang of computing wheels, 85 extensions on said stops, of two kinds, a pair of separably operable cam bars each moved by one kind of extension, a shaft to which one arm is fast, a sleeve on said shaft to which the other is fast, and means for controlling said gangs from said sleeve and shaft.
11. In a combined typewriting and computing machine, the combination with numeral keys and a traveling carriage, of a 90 plurality of gangs of computing wheels, stops on said traveling carriage, a master wheel for each gang of computing wheels, 95 extensions on said stops, of at least two kinds, a cam bar for each kind of extension, means controlled by said cam bars for controlling said master wheels, all said cam bars covering the same travel of the carriage, and a shaft constituting a single axis about which said cam bars swing.
12. In a combined typewriting and computing machine, the combination with numeral keys and a traveling carriage, of a 100 plurality of gangs of computing wheels, a master wheel for each gang, a rack bar, stops on said rack bar, extensions of at least two kinds on said stops, a cam bar for each kind of extension, all of said cam bars covering the same travel of the carriage, rock arms lying in one plane carrying said cam bars, connections between said rock arms and said master wheels, said rock arms bent in said plane so as to swing free of each other, and a shaft constituting a 105 single axis about which said cam bars swing.
13. In a combined typewriting and computing machine, the combination with numeral keys and a traveling carriage, of a 110 plurality of gangs of computing wheels, a master wheel

- for each gang, a rack bar, stops on said rack bar, extensions of at least two kinds on said stops, a cam bar for each kind of extension, all said cam bars covering the same travel of the carriage, clutches for said master wheels at one end of the machine, rock members connecting said cam bars to links at said end, and means for shifting said clutches by said links.
- 10 14. In a combined typewriting and computing machine, the combination with numeral keys and a traveling carriage, of a plurality of gangs of computing wheels, stops on said traveling carriage, a master wheel for each gang of computing wheels, means including a lever swinging transversely of the machine for connecting said carriage to a master wheel, and means including a bell crank at one end of the machine swinging vertically to control the revolution of said master wheel by said keys.
- 15 15. In a combined typewriting and computing machine, the combination with a traveling carriage, of a stop on said carriage for locking said carriage, a cross adding mechanism, and means controlled by said stop for determining how said machine shall do such cross adding, and whether it shall add or subtract.
- 20 16. In a combined typewriting and computing machine, the combination with a traveling carriage, of a bar on said carriage, stops on said bar, computing mechanism adapted to compute repeatedly during the travel of said carriage, and means for arresting said carriage by said stops and repeatedly connecting the adding mechanism and simultaneously determining whether said mechanism shall add or subtract.
- 25 17. In a combined typewriting and computing machine, the combination with a plurality of computing heads, of a traveling carriage, stops settable on said carriage, means controlled by said stops to determine separately whether said heads shall add or subtract, and means also controlled by said stops and connectible to any one of them for determining in what letter space said heads shall begin to compute.
- 30 18. In a combined typewriting and computing machine, the combination with a plurality of gangs of computing wheels, of a traveling carriage, tabulating stops settable on said carriage, and means connected to said tabulating stops for separately determining whether said heads shall add, subtract or be neutral.
- 35 19. In a combined typewriting and computing machine, the combination with numeral keys and computing wheels, of a device for determining how far said computing wheels shall be turned by the operation of said keys, a clutch for each computing device for determining how said wheels shall be turned, a tabulating stop settable on
- said carriage and means controlled by said stop to determine in what column said computing devices shall be effective.
- 40 20. The combination with a carriage, of a convertible computing head, clutches for converting said computing head, column-stops carried by said carriage and means controlled by said stops for shifting said clutches. 70
- 45 21. The combination with a traveling carriage, of a convertible computing head, mechanism for converting said computing head, a tabulator stop for said carriage, and means enabling said stop to convert said computing head. 75
- 50 22. In a combined typewriting and computing machine, the combination with a plurality of computing heads, of state-controlling mechanism for said computing heads, a traveling carriage, a tabulator stop carried by said carriage, and means enabling said stop to control the state of all of said computing heads concomitantly. 80
- 55 23. In a combined typewriting and computing machine, the combination with a plurality of computing heads, of state-controlling mechanism for said computing heads, a traveling carriage, tabulator stops carried by said carriage, zonal cams arranged adjacent said carriage and co-operating with said stops and means connecting said zonal cams and state-controlling mechanism whereby said stops, during the travel of said carriage, may variously control the state of said computing heads in the several computing zones determined by the carriage travel. 90
- 60 24. The combination with a traveling carriage, of a plurality of computing heads, a controlling mechanism individual to each computing head for governing the state thereof as to the activity and character of computation carried on thereby, each of said controlling mechanisms including a member with a bearing surface extending in the direction of travel of said carriage and of a magnitude corresponding to a desired computing zone, said bearing surfaces of the several members being arranged to control the same computing zone or column, and an assortment of tappets, each capable of being carried by said carriage and individually formed to engage singly either one or another or a plurality of said bearing surfaces. 105
- 65 25. The combination with a traveling carriage, of a plurality of computing heads, a controlling mechanism individual to each of said computing heads, each of said controlling mechanisms having a member with a bearing surface arranged in juxtaposition to said carriage, an assortment of tappets, each capable of being carried by said carriage into engagement with said bearing surfaces, said tappets traveling in a path in the 110
- 70 120
- 75 125
- 80 130

- direction of movement of said carriage, and said bearing surfaces congregating for the extent of a computing zone in the path of said tappets, so as to be operated simultaneously by such of said tappets singly as may be formed to operate them.
26. The combination with a traveling carriage, of a plurality of computing heads, a controlling mechanism individual to each of said computing heads for governing the state thereof, connections individual to each of said controlling mechanisms for operating the same, and one or more tappets carried by said carriage for operating said connections, each of said connections including an arm having a bearing surface extending in the general direction of the travel of said carriage to be operated by said tappets for a period of movement of said carriage, a plurality of coaxial members connected individually to said arms to be rocked thereby, and linkages connecting said coaxial members with said controlling mechanisms.
27. The combination with a carriage, of a plurality of computing heads, controlling mechanisms individual to said computing heads for governing the state thereof, and a series of tappets common to all said controlling mechanisms having different conformation corresponding to all possible combinations of states of said computing heads and arranged to actuate said controlling mechanisms.
28. The combination with a traveling carriage, of a computing unit including a computing head and a master wheel, said computing head and said master wheel having a relative traveling movement to enable the running up of digits into said computing head digit by digit, vibrating mechanism for effecting the relative movement between said computing head and said master wheel, controlling mechanism for governing the state of said computing unit as to the character of computation carried on thereby, tabulating mechanism for determining the position of said carriage for a computing zone or column, and a tappet carried by said carriage, coöperating with said vibrating mechanism to actuate the same and cause a relative movement between said master wheel and said computing head, coöperating with said state-controlling mechanism to vary the state or character of computation of said computing unit, and coöperating with said tabulating mechanism to determine the position of said carriage.
29. The combination with a traveling carriage, of a computing unit including a computing head and a master wheel, said computing head and said master wheel having a relative traveling movement to enable the running up of digits into said computing head digit by digit, vibrating mechanism for effecting the relative movement between said computing head and said master wheel, said computing head and said master wheel having the extent of a computing zone in the path of said tappets, so as to be operated simultaneously by such of said tappets singly as may be formed to operate them.
30. The combination with a traveling carriage, of a computing unit including a computing head and a master wheel, said computing head and said master wheel having a relative traveling movement to enable the running up of digits into said computing head digit by digit, vibrating mechanism for effecting the relative movement between said computing head and said master wheel, controlling mechanism for governing the state of said computing unit as to the character of computation carried on thereby, tabulating mechanism for determining the position of said carriage for a computing zone or column, and a tappet carried by said carriage, coöperating with said vibrating mechanism to actuate the same and cause a relative movement between said master wheel and said computing head, coöperating with said state-controlling mechanism to vary the state or character of computation of said computing unit, and coöperating with said tabulating mechanism to determine the position of said carriage, said tappet being one of several of different conformations corresponding to different actions thereof.
31. The combination with a computing head, of a master wheel for running up digits in said computing head digit by digit, a power drive for said master wheel, means for changing the direction of drive of said master wheel by said power drive, a traveling carriage, and one or more tappets carried by said carriage connected to enable the force of said carriage in traveling to shift said drive-changing means to change the direction of drive of said master wheel.
32. In a combined typewriting and computing machine, the combination with a gang of computing wheels, of numeral keys for controlling the rotation of said computing wheels, a traveling carriage, tabulating mechanism for positioning said carriage and including stops, a bar adjacent the path

of movement of said stops and means enabling said bar to control the connection of said keys to said computing wheels, and a lug on a stop for operating said bar in a predetermined zone as determined by the travel of said carriage.

33. The combination with a computing unit, of a carriage traveling to determine computing zones, tabulating mechanism for determining the stopping points or zones of said carriage, and including tabulating stops carried by said carriage, said tabulating stops having various forms, and controlling mechanism for said computing unit 10 operated from said stops to govern the character of computation of said computing unit in accordance with the particular conformation of the tabulating stop in action at any particular instant.

20 34. The combination with a computing unit including a gang of computing wheels and a master wheel, of a traveling carriage, and a plurality of tappets of various forms carried by said carriage and means to enable said tappets to control the rotation and direction of rotation of said master wheel according to their forms.

35. The combination with a computing unit including a gang of computing wheels, 30 and a master wheel for driving said computing wheels *seriatim*, of a traveling carriage, a controlling mechanism for governing the rotation and direction of rotation of said master wheel, so as to determine the 35 activity of said computing unit, and whether said computing unit will add or subtract, and a plurality of differently formed tappets carried by said carriage and connected to determine the adjustment of said controlling mechanism in accordance with their 40 own forms, which are arranged to predetermine the rotation and direction of rotation of said master wheel for different positions of said carriage.

45 36. The combination with a computing unit including primary elements, to wit, a gang of computing wheels and a master wheel, acting within a limited range so that said master wheel can register *seriatim* with each of said computing wheels, a carriage traveling to determine a plurality of computing zones, the primary elements of said computing unit having a repeated relative movement over the same range for successive computing zones of said carriage, and a plurality of variously formed tappets connected to control, for successive computing zones, the rotation and direction of rotation of said master wheel.

60 37. In a combined typewriting and computing machine, the combination with a computing head, of a traveling carriage, a typewriter tabulating mechanism therefor including a reversible tabulator stop carried 65 by said carriage, and means for differently

controlling said computing head as to its state depending on whether said stop is in one position or another, said stop capable of performing its tabulating function in either position.

70

38. The combination with a computing unit, of a traveling carriage, tappets carried by said carriage, a cam operated by said tappets, and an intermediary mechanism interposed between said cam and said computing unit for enabling said tappets to control the computation and character of computation carried on by said computing unit.

75

39. In a combined typewriting and computing machine, the combination with a plurality of computing heads, of a traveling carriage, a plurality of tabulator stops for controlling said carriage, said stops having conformations differing on different stops, 80 and means enabling said stops, in a single traverse of said carriage, to produce by means of said conformations all combinations of states of said computing heads.

40. In a combined typewriting and computing machine, the combination with a plurality of computing heads, of a traveling carriage, a tabulator stop controlling said carriage and connections between said stop and said computing heads, said stop having 95 such configurations that it may differently determine the combinations of states of said computing heads according to whether said stop is in one position or another.

90

41. The combination with a traveling carriage, a computing head, a master wheel therefor, said carriage connected to effect relative travel between said computing head and said master wheel, and converting mechanism for said computing head, of a tappet, 100 and means to enable said tappet to determine the character of computation to be performed at any selected letter-space position of the carriage, including a cam member engageable by the tappet and connected to 105 said converting means to operate the same.

100

42. The combination with a traveling carriage, a computing head, a master wheel therefor, said carriage connected to effect relative travel between said computing head and said master wheel, and converting mechanism for said computing head, of a series 115 of assorted tappets, and means to enable any of said tappets to determine the character of computation to be performed at any selected letter-space position of the carriage, including a cam member capable of being engaged and variably controlled by the different tappets and connected to said converting means to operate the same.

110

43. The combination with a traveling carriage, a plurality of computing heads, and individual master wheels therefor, said carriage connected to effect relative travel between said computing heads and said master 120 wheels.

120

125

130

- wheels, of individual converting mechanisms for said computing heads, a tappet, and means to enable said tappet to determine the character of computation to be performed 5 in each computing head at any selected letter-space position of the carriage, including cam members individual to said converting mechanisms to operate the same, and capable of being simultaneously controlled by 10 said tappet.
44. The combination with a traveling carriage, a plurality of computing heads, and individual master wheels therefor, said carriage connected to effect relative travel between said computing heads and said master wheels, of individual converting mechanisms for said computing heads, cam members individual to said converting mechanisms to operate the same, and an assortment 15 of adjustable tappets, each capable of being brought into use by said carriage, one to engage only one of said cam members, another to engage only another of said cam members, and another to engage both of said 20 cam members.
- 25

45. The combination with a traveling carriage, of a plurality of tandem or axially offset computing heads, individual tandem or axially offset master wheels therefor, said carriage connected to effect relative travel 30 between said computing heads and said master wheels, and the tandem arrangement of the computing heads and the master wheels rendering each computing head incapable of engagement by the master wheel of the other 35 computing head at any part of the entire range of travel of the carriage, individual converting mechanisms for said computing heads, and adjustable means to enable said carriage to determine the character of computation to be performed in each computing head at any selected letter-space position of the carriage, including cam members individual to said converting mechanisms to 40 operate the same, and capable of being simultaneously controlled by said carriage.
